CRANK PIN GRINDER

Carl J. Cook, Kirwin, Kans.

Application May 21, 1938, Serial No. 209,342

3 Claims. (Cl. 51—131)

This invention relates to crank pin grinders, and has for one of its objects the production of a simple and efficient means for grinding a crank pin and efficiently holding the grinding tool in connection with the crank pin, whereby the various parts of the device are automatically adjusted and the grinding wheel is held in contact with the crank pin during its rotation.

A further object of this invention is the production of a simple and efficient mounting for a crank pin grinder which may be attached to the carriage of an ordinary engine lathe to hold the grinding wheel in firm contact with the surface of a crank pin as the crank pin or shaft rotates.

Other objects and advantages of this invention will appear throughout the following specification and claims.

In the drawings:

Figure 1 is a side elevational view of the crank pin grinder, mounted upon a lathe, certain parts being broken away and shown in section;

Figure 2 is a top plan view of the grinder, a portion of a crank pin or shaft being shown, and certain parts of the grinder being shown in section;

Figure 3 is a vertical sectional view taken on line 3—3 of Figure 1;

Figure 4 is a vertical sectional view taken on line 4—4 of Figure 1;

Figure 5 is a vertical sectional view taken on line 5—5 of Figure 1;

Figure 6 is a vertical sectional view taken on line 6—6 of Figure 1;

Figure 7 is a vertical sectional view taken on line 7—7 of Figure 1.

By referring to the drawings, it will be seen that 10 designates the conventional engine lathe which carries a conventional lathe carriage 11 upon which is secured a working table 12 through the medium of the headed bolts 13 which fit within the dove-tail slots 14 formed in the lathe carriage 11. This table 12 is provided with a dove-tail tongue 15 upon which is slidably mounted a slidably adjustable block 16 carrying a journal pin 17 upon which journal pin is secured a hanger 18. The block 16 is adapted to move longitudinally of the table 12, and the hanger 18 is adapted to rock upon the journal 17.

This hanger 18 supports an arm 19 which carries the motor supporting plate 20 and a motor 21 is mounted upon the plate 20 in any suitable or desired manner. The motor 21 is provided

with an upwardly extending shaft 22 carrying a pulley 23 around which a belt 24 passes.

The hanger 18 also carries a forwardly extending rocker arm 25 which is secured near the lower end of the hanger 18 and extends forwardly to support the grinding mechanism. In carrying out the invention, the crank shaft 26 or work upon which the grinding is to take place is held between the lathe centers in the conventional manner, and the table 12 which supports the grinding mechanism, is carried by the lathe carriage 11, as previously described.

The forward end of the rocker arm 25 carries a machine grooved block 27 upon which is slidably mounted an adjustable jaw 28 having a V-shaped work-gripping end 29. The adjustable jaw 28 is engaged by an adjusting screw 30 which is threaded through a collar 31 supported upon a bracket 32 fixed to the block 27 and the forward end of the rocker arm 25 as shown. A suitable handle 33 is carried by the screw 30 to facilitate the adjustment of the adjustable jaw 28.

A stationary jaw 34 is anchored in a set position upon the rocker arm 25 and is provided with a V-shaped work-engaging end 35, the crank pin 36 of the crank shaft 26 being adapted to fit between the V-shaped ends 29 and 35 of the respective adjustable and stationary jaws 28 and 34 to attach the rocker arm to the pin and cause the rocker arm to move as the crank shaft 26 is moved or rotated upon the lathe in the conventional manner. By noting Figure 1 it will be seen that the conventional lathe face plate is indicated by the numeral 37. The stationary jaw 34 is provided with a longitudinal channel 38 in which is slidably and adjustably mounted a shaft 39, and this is held in position by a suitable clamp 40 at the end thereof. The shaft 39 is provided with a pair of upstanding ears 41 upon which ears is pivotally mounted a depending tongue 42 of a square sliding bar or head 43. A journal pin 44 is provided for connecting the head 43 with the shaft 39, as shown in Figure 3. This head 43 is slidably mounted with a square upwardly extending aperture 45 formed in the upwardly extending guide 46. The guide 46 is provided with laterally extending journals 47 through which an adjusting screw 48 is threaded, the screw 48 having an operating handle 49 at its upper end to facilitate the operation thereof. The lower end of the screw 48 is connected to the upper face of the stationary jaw 34 by means of a ball and socket connection 50 so as to allow the upwardly extending guide 46

to be swung toward or away from the work as the screw 48 is adjusted, this being possible due to the sliding of the head 43 within the guide 46. The guide 46 also carries an upwardly extending sleeve 51 upon its front face within which sleeve is rotatably mounted a grinding spindle 52 carrying a pulley 53 at its upper end around which the bolt 26 previously mentioned passes. The grinding spindle 52 carries a grinding element 54 at its lower end which may be secured to the spindle 52 in any suitable or desired manner, such for instance as by means of a threaded cap 55.

From the foregoing description it will be seen that a very efficient and simple means has been provided for attaching the mechanism to the crank pin by means of the jaws 34 and 28, whereby the crank pin may be held against displacement from engagement with the grinding apparatus. The crank shaft as stated previously, is held between the lathe centers and is adapted to rotate, the sliding block 16 reciprocating upon the table 12 as the crank shaft rotates and the hanger 18 rocking upon its journal 17, thereby allowing the parts to automatically adjust themselves and follow the movement of the crank shaft 26 in its rotation. The grinding spindle 52 is driven by means of the belt 24 from the motor 28 and the grinding element 54 is moved to the proper position by the adjustment of the shaft 39 and a proper pressure is maintained between the crank pin 36 and the grinding element 54 through the adjustment of the screw 48 to keep a proper pressure of the grinding element 54 upon the surface 35 of the crank pin 36 which is being ground. The jaw 28 is, of course, adjusted properly to permit the crank pin 36 to rotate between the adjustable and stationary jaws and the screw 48 may be adjusted to maintain a proper pressure of the grinding element 54 upon the pin 36. The rotation of the crank shaft 26 will cause all of the parts with the exception of the table 12, to move and accommodate themselves to a proper position as the shaft 26 rotates.

It should be understood that certain detail changes in the construction and arrangement of parts may be employed without departing from the spirit of the invention, so long as such changes fall within the scope of the appended claims.

Having described the invention, what I claim as new is:

1. A crank pin grinding device of the class described comprising a table, a crank shaft supporting means carried by the table, a member slidably mounted for longitudinal movement upon the table, a hanger journaled and suspended from said slidably mounted member, a rocker arm suspended on said hanger, a stationary jaw carried by said rocker arm and adapted to engage a crank pin, an adjustable jaw adjustably mounted upon the rocker arm for engaging the crank pin and holding the rocker arm in association with the crank pin, a grinding spindle supported at approximately right angles to the stationary jaw,

a grinding member carried by the spindle, means for adjusting the spindle toward and away from the stationary jaw, means for rotating the spindle, means for supporting the spindle, means for adjusting the spindle longitudinally of the stationary jaw, and means for adjusting the angular position of the spindle with respect to the stationary jaw and moving the spindle toward and away from the work adapted to be carried by the stationary and adjustable jaws. 5

2. A crank pin grinding device of the class described comprising a supporting table, a crank shaft supporting means carried by said table, a rocker arm suspended upon the supporting table at one end and having upward and downward swinging movement with respect to the table, means for supporting the rocker arm upon the table, said means being adjustable longitudinally of the table, a crank pin engaging means carried by the rocker arm for connecting the rocker arm 10 with a crank pin, a grinding mechanism comprising a longitudinally adjustable supporting member carried by the rocker arm, an upstanding member pivotally secured to said supporting member, an outwardly sliding head carried by 15 said upstanding member, a rotating spindle carried by said sliding head, a grinding member carried by the spindle, means for rotating said spindle, a threaded rod carried by said supporting member and pivoted thereon, and means carried by the sliding head and engaging said adjustable member for moving the rotating spindle to and from a crank pin carried by the rocker arm. 20

3. A crank pin grinding device of the class 35 described comprising a supporting table, a crank shaft supporting means carried by said table, a rocker arm suspended upon the supporting table at one end and having upward and downward swinging movement with respect to the table, means for supporting the rocker arm upon the table, said means being adjustable longitudinally 40 of the table, a crank pin engaging means carried by the rocker arm for connecting the rocker arm with a crank pin, a grinding mechanism comprising a longitudinally adjustable supporting member carried by the rocker arm, an upstanding member pivotally secured to said supporting member, an outwardly sliding head carried by 45 said upstanding member, a rotating spindle carried by said sliding head, a grinding member carried by said spindle, means for rotating said spindle, a threaded rod carried by said supporting member and pivoted thereon, means carried by the sliding head and engaging said adjustable member for moving the grinding spindle to and from a crank pin carried by the rocker arm, said 50 means for rotating the spindle comprising a driving motor suspended by said rocker arm and constituting a counter-balance for said rocker arm, and means connecting the motor with the rotating spindle. 55

CARL J. COOK.
